UNITED STATES PATENT OFFICE.

JAMES JOSEPH WARREN, OF SEATTLE, WASHINGTON.

EXCAVATOR.

1,345,296.

Specification of Letters Patent. Patented June 29, 1920.

Application filed July 3, 1919. Serial No. 308,420.

To all whom it may concern:

Be it known that I, JAMES J. WARREN, a citizen of the United States, and a resident of Seattle, in the county of King and State 5 of Washington, have invented a new and Improved Excavator, of which the following is a full, clear, and exact description.

This invention relates to excavators, and more particularly to a machine of this kind 10 for use in cutting tunnels, ditches, trenches and the like, in connection with mining, agricultural, and similar activities.

The object of the invention is to provide a simple and efficient excavating machine by 15 means of which tunnels, ditches, trenches and the like may be dug rapidly, with small expenditure of power, and with the aid of a minimum of operators or workmen.

A further object of the invention is to 20 provide an excavator which can be easily handled and maneuvered, which is self-driven, and in which a single prime mover is used both for the operation of the excavator and its travel and maneuvering.

Reference is to be had to the accompanying 25 drawings forming a part of this specification, in which similar characters of reference indicate corresponding parts in all the views, and in which—

Figure 1 is a side elevation of my excavator, showing the same in operation in digging a tunnel;

Fig. 2 is a plan view of the excavator, having parts thereof broken away;

Fig. 3 is a longitudinal, vertical section on the line 3—3 of Fig. 2;

Fig. 4 is a rear end elevation of the excavator;

Fig. 5 is a transverse, vertical section on the line 5—5 of Fig. 1; and

Fig. 6 is a fragmentary, partial, cross-sectional side elevation of a slide bearing of the machine.

Before proceeding to a more detailed explanation of my invention it should be understood that while the excavator as illustrated is shown in operation digging a tunnel, it can also be advantageously employed in digging trenches, ditches, in open mining, 45 and for other purposes. It is intended primarily for operation in comparatively soft material such as sand, earth, or gravel, but can also be used in mixtures of material including comparatively small rocks or boulders. As exemplified herein the prime mover for providing power for the opera-

tion of the excavator is an electric motor to which current may be supplied in any convenient manner. However, other prime movers such as gas or oil engines may be 60 used. Many of the details of construction illustrated herein may be varied, and form no part of the invention.

Referring more particularly to the drawings, the excavator has a body 10 providing 65 a platform 11 arranged comparatively close to the ground and having mounted thereon the electric motor 12 or any other suitable source of power. The sides of the body consist of two spaced uprights 13 and 14, 70 the uprights 13 being substantially vertical and at the rear of the body, and the uprights 14 being at the forward part of the body and rearwardly inclined. The uprights of each pair are connected at their upper ends 75 by longitudinal members 15 having mounted thereon bearings 16 in which is journaled a main shaft 17 extending transversely of the excavator. The lower parts of the upright 13 at the rear of the body are connected by 80 a cross wall 18 having a rearward, horizontal extension 19. A fork member 20 is mounted under the extension 19 and is pivotally associated therewith by means of a king pin 21 extending through an opening 85 provided for the purpose in the extension. A guide wheel 22 having a central, peripheral flange 23 is rotatably mounted between the sides of the fork member. A retaining collar 24 is secured upon the king pin, above 90 the extension 19. The king pin also has rigidly associated therewith an arm 25 extending forwardly of the excavator and carrying at its free end a toothed segment 26 in mesh with a worm 27 carried upon a 95 shaft 28 mounted in bearings 29 carried by the uprights 13. At one end, the shaft 28 has a hand crank 30, by means of which the shaft may be turned. The movement of the shaft through the worm and toothed segment will swing the guide wheel 22 in one direction or the other, as desired.

The motor 12 is operatively connected with the shaft 27 in any suitable manner, for example as shown, by means of gears 105 and pinions. In the exemplification of the machine illustrated, a pinion 31 is mounted upon the shaft 32 of the motor. This pinion is in mesh with a gear 33 carried by an intermediate shaft 34. This shaft likewise 110 carries a pinion 35 in mesh with a gear 36 mounted upon the main shaft 17.

The excavator includes a swinging frame consisting of suitable, similar side frame members 37, of any suitable form, and preferably consisting of I-beams or channels. 5 Each frame member 37, at its end, has bearings 38 and 39, respectively at the forward and rear ends. In the bearings 38 is mounted a shaft 40, and in the bearings 39, a shaft 41. The shaft 40 carries a pair of spaced 10 disks 42 having spaced peripheral guides 43. Similar disks 44, having peripheral notches 45, are secured upon the shaft 41. Arranged upon the upper edges of each of the frame members 37 is a series of bearings 46, 15 each corresponding pair of bearings having a transverse shaft 47 carrying near its ends and within the space between the frame members, flanged idler rollers 48. The excavating element of the machine 20 consists of a series of buckets mounted upon chains and arranged to travel around the swinging frame. This series of chain buckets may be of any suitable type or form, and, for example, as shown herein, each bucket 25 has an outer face 49, preferably of arcuate cross-section, a rear wall 50, and side walls 51 of substantially triangular shape. The chains proper consist of pairs of spaced links 52 arranged along the edges of the 30 rear walls of the buckets and connected by suitable hinge rods 53, the links of each pair being held apart by spacers 54 mounted upon the rods 53. The chains pass around the guide disks 42 and 44, the notches of 35 which are so spaced as to receive the rods 53 and the spacers thereon, in the usual manner. The upper runs of the chains are supported movably upon the rollers 48, the flanges of which serve to restrain the loaded 40 buckets from lateral movement. Preferably, the curved face 49 of each bucket is provided with two or more prongs or teeth 55 the points of which project beyond the edges of the buckets, to facilitate the digging action. Preferably, the prongs of the 45 different buckets are variously spaced, as is shown in Figs. 4 and 5.

The body of the excavator, at the forward lower part thereof, carries a pair of spaced 50 upwardly directed arcuate arms 56, each presenting a rack 57 at its rear edge. The racks 57 mesh with pinions 58 mounted upon a shaft 59 journaled in the frame members 37. Between the frame members 55 the shaft 59 carries a bevel gear 60 in mesh with a bevel gear 61 carried upon the forward end of a longitudinal shaft 62 journaled in a bearing 63 of a cross-frame member 64. At its rear end, the shaft 62 carries a bevel gear 65 adapted to mesh with either one of two oppositely disposed bevel gears 66 and 67, rigidly secured upon the main shaft 17. A shaft 68 is journaled in bearings carried by the body, at the upper part 60 thereof, and has at one end a hand wheel 69.

Intermediate its ends, the shaft 68 has a worm 70 arranged to coöperate with a block 71 through which the shaft 62 rotatably passes. Thus, by turning the hand wheel 69, the block 71 can be moved in one direction or the other, carrying with it the shaft 62, which is so mounted as to have some lateral play. In this way the bevel gear 65 can be caused to mesh with the bevel gear 66 or the bevel gear 67, at the will of the 75 operator.

Tie-bars 72 and 73 connect respectively the ends and the intermediate parts of the arms 56 with the body of the machine, to stiffen and strengthen the arms 56. Rotatably mounted in bearings 74 carried by the arms 56 are independent but similar traction wheels 75, having hubs 76, spokes 77, outer rims 78, and inner rims 79 concentric with the outer rims and spaced inwardly therefrom. Preferably, the traction wheels have the outer peripheries of the rims 78 provided with projections or ribs 80 in order to increase the tractive effort, by insuring suitable engagement with the 90 ground.

Each of the body members 14 has mounted thereon, at its forward edge, a U-shaped slide bearing member 81 in which is mounted slide bearings 82. A transverse shaft 83 is 95 carried in the slide bearings 82. This shaft has mounted thereon a pair of spaced disks 84 having peripheral notches 85 and similar to the disks 42 and 44. The disks 84 are located under the bucket frame and serve as 100 idlers, engaging the lower runs of the chains whereby the shaft 83 is constantly actuated when the chain of buckets is in operation. The shaft 83, at each end, has a roller 86 located in the inner and outer rims of one of 105 the traction wheels. Associated with each slide bearing 82 is a threaded stem 87 passing through a threaded opening 88 of the frame member 14 and having secured thereto a hand wheel 89. By turning the hand 110 wheel 89, the corresponding slide bearing can be moved backward and forward to bring the roller 86 into frictional engagement either with the inner or the outer rim of the traction wheel, the arrangement of 115 the shaft 83 permitting sufficient play for the purpose.

The power from the main shaft 17 is transmitted to the chain of buckets by means of a sprocket 90 on the main shaft, a chain 120 91 and a second sprocket 92 rigidly secured upon the shaft 41.

The operation of the excavator is as follows:

When the motor 12 is set in motion its 125 power is transmitted through the gears and pinions to the main shaft 17, upon which the bucket frame is mounted to swing. The power from the main shaft 17 is transmitted to the chain of buckets by means of the 130

sprocket 90 on the main shaft, the chain 91 and the sprocket 92 on the shaft 41. The endless chain of buckets travels around the disks 42 and 44 and over the idler rollers 48 and the idler disks 84. By suitably positioning the machine, the buckets at the front end of the frame are brought into engagement successively with the material to be excavated, in the customary manner.

10 In order to lift or lower the frame, which is pivoted at about one-fourth its length from its rear end, so that its forward end has a far greater range of swing than its rear end, the hand wheel 69 is turned to bring the bevel gear 65 into engagement with the bevel gear 66 or 67. Thus the power of the shaft 17 is transmitted to the shaft 59, turning the same in one direction of the other. This movement thus serves to 20 raise or lower the frame through the coöperation of the pinions 58 with the rack 57.

To propel the machine forward or backward the hand wheels 89 are turned to retract the slide bearings 82 to bring the vertical rollers 86 into engagement with the inner sides of the traction wheel rims 78, thus causing the wheels to be turned forward. To cause the excavator to travel rearwardly, the friction rollers are brought into engagement with the inner rim 79. It will be understood that the shaft 83 is constantly turned as long as the bucket chain is in operation, so that power to propel the excavator is derived from the chain of excavating elements. To facilitate the turning of the excavator in one direction or the other, without any appreciable forward or backward movement of the machine as a whole, one only of the friction rollers may be rendered operative with respect to its corresponding traction wheel, the guide wheel 22 being suitably turned at the same time by means of its controlling devices.

As the rear end of the bucket chain projects beyond the body of the machine, a wagon or dump car 93 may be brought under the rear of the bucket chain to receive the material from the buckets as the same pass around the disks 44.

50 The excavator as employed herein is designed primarily for cutting tunnels, in mining operations. To adapt it for the cutting of trenches, ditches and the like, more readily, the racks 57 of the arms 56 may be continued downwardly farther toward the lower ends of these arms, so that the cutting end of the bucket chain may be lowered a greater distance below the surface of the ground.

60 Having thus described my invention, I claim as new and desire to secure by Letters Patent:—

1. An excavator comprising a body having independent traction wheels, an endless

chain of excavator buckets, means for driving said chain, and means driven from said chain, for independently actuating said traction wheels. 65

2. An excavator comprising a body having independent traction wheels and a guide 70 wheel, a main shaft journaled on said body, a frame mounted to swing upon said shaft, an endless chain of excavator buckets movably mounted upon said frame, a prime mover, means for driving said excavator 75 chain from said main shaft, means operatively connecting said prime mover and said main shaft, means for lowering and raising said frame and swinging the same upon said main shaft, means for operatively connecting said last-mentioned means and said main shaft at will, and means for actuating said traction wheels from said excavator chain. 80

3. An excavator comprising a body having a prime mover mounted thereon and provided with an arcuate, upwardly extending arm having a rack, a main shaft journaled on said body, a frame mounted to swing upon said main shaft, means for operatively connecting said prime mover and said main 90 shaft, a movable chain of excavator buckets carried by said frame, means driven from said chain for propelling said body, means for operatively connecting said main shaft and said movable excavator chain, said 95 frame carrying a second shaft having a pinion in mesh with said rack, and means for operatively connecting and disconnecting said main shaft and said other shaft at will.

4. An excavator comprising a body having 100 a prime mover mounted thereon and provided with an arcuate, upwardly extending arm having a rack, a main shaft journaled on said body, a frame mounted to swing upon said main shaft, means for operatively 105 connecting said prime mover and said main shaft, a movable chain of excavator buckets carried by said frame, means for operatively connecting said main shaft and said movable excavator chain, said frame carrying a 110 second shaft having a pinion in mesh with said rack, means for operatively connecting and disconnecting said main shaft and said other shaft at will, said body having independent traction wheels, and independent 115 means for operatively connecting said movable excavator chain and said traction wheels at will.

5. An excavator comprising a body having independent traction wheels and a guide 120 wheel, a main shaft journaled upon said body, means for driving said shaft, an elongated frame mounted to rock upon said main shaft, means for rocking said frame upon said main shaft, an endless chain of excavator buckets mounted upon said frame, means for driving said chain from said main shaft, a countershaft in operative relation 125

with a run of said chain, and independent means for actuating said traction wheels from said countershaft.

6. An excavator comprising a body having at the forward end spaced, upwardly extending arcuate arms each having a rack, a traction wheel journaled upon each of said arms, a main shaft journaled on said body, an elongated frame mounted to rock upon said main shaft, and located between said arms, means for driving said main shaft, an endless chain of excavator buckets carried by said frame, means for driving said chain from said main shaft, said frame having a second shaft provided with pinions in mesh with said racks, shaft and gearing mecha-

nism for operatively connecting said main shaft and said second shaft for rocking said frame at will, sprockets operatively connected with said chain, independent friction rollers for engaging the rims of said traction wheels, a common shaft for said sprockets and said friction rollers, and means for moving said last-mentioned shaft to bring said rollers into and out of operative relation with the rims of said traction wheels.

7. In an excavator, an endless chain of excavator buckets, a countershaft associated with a run of said chain and rotated thereby, traction means, and means for actuating said traction means from said counter-shaft.

JAMES JOSEPH WARREN.
